DAVID SILBERMAN, OF NEW YORK, N. Y.

HOOK AND EYE TAPE.

Application filed July 28, 1924. Serial No. 728,645.

My invention relates to hook and eye tapes and it is my object to produce a strong tape which can be readily attached to a garment and to which the hooks and eyes are securely fastened with the bases of the hooks concealed and protected. Another object is the production of a new form of tape, woven integrally with flaps or plies to obviate the necessity of sewing two or more strips of fabric together.

In the drawing Fig. 1 is a face view of my hook and eye tape; Fig. 2 a sectional view of the eye tape on the line 2—2 of Fig. 1; and Fig. 3 a sectional view of the hook tape on the line 3—3 of Fig. 1.

To produce my improved tape a specially woven fabric having a single ply at one side and a double ply at the other side is employed so that the tape itself is integral and not made of two or more pieces sewed together.

In the eye tape member the single ply 1 divides into two plies 2 and 3 at about its median line, as shown in Fig. 2, the two plies 2 and 3 being practically the same width. The eyes 4 are held to the ply 2 by rivets 5, although fastening means other than rivets may be employed.

By riveting the eyes to the outer ply 2 and using the base or under ply 3 as a protector for the base of the rivets 5 the rivets are prevented from cutting the garment to which the tape is sewed or from rubbing against the skin of the wearer. This is desirable on the eye strip as the hook strip is outside of and above the eye strip when the tapes are hooked together.

By weaving the "three edged" tape as a unit the handling of two pieces and sewing them together is avoided and any folds which might otherwise be necessary to finish the

edges are unnecessary, thereby reducing the thickness of the finished tape.

In use the edge of a garment is slipped between the plies 2 and 3 and the three parts 4 sewed together, the single ply 1 extending forwardly under the eyes as a flap.

In making the hook tape member the unitary tape is employed but the single ply 6 is less than half the width of the tape while 50 the ply 7 does not extend to the edge of the ply 8 as is shown in Fig. 3. The hooks 9 are secured to the ply 8 by rivets 10 but other fasteners may be employed. The ply 7 extends over the hook bases and rivets and 55 under the bills of the hooks. The plies 7 and 8 may be sewed together by a line of stitching 11 if desired.

In use the ply 6 is sewed to the edge of a garment opposite the eye tape member and 60 the hooks and eyes may be readily engaged without any danger of catching on the hook bases and rivets which are protected by the ply 7.

While I have shown the invention applied to hook and eye tape it is obvious that other fasteners may be substituted on the multiply integrally woven tape which forms the foundation of my invention.

I claim:—

Eye tape comprising a strip of integrally woven tape having a single ply at one edge divided into two plies at about its median line, a plurality of spaced eyes secured to one of the latter plies, the operative portions 75 of said eyes extending over the single ply and adapted to have a garment edge inserted between the two plies.

In testimony whereof I have affixed my signature.

DAVID SILBERMAN.
